MACHINE FOR PRODUCING COMPRESSED FEEDS

Duane Crabtree, Springfield, Oreg., assignor to
 Western Pellet Machine Corporation, Eugene,
 Oreg., a corporation of Oregon

Application December 17, 1938, Serial No. 246,434

18 Claims. (Cl. 107—8)

This invention relates to machines for compressing plastic or non-plastic materials into different types of feeds. The invention particularly relates to improvements in machines for compressing feeds through more than one die by the use of revoluble members having their peripheral surfaces in operative contact with each other.

Briefly stated, the machine consists of a compressor wheel assembly and a die assembly, the external peripheral surfaces of which contact each other, not only to impart rotation to the compressor wheel, but also to force material through passages in the dies. Provision is made for regulating the position of the compressor wheel with respect to the die assembly. Means are also provided for insuring against rearward or forward movement of the compressor wheel and die assembly.

One of the objects of the invention is to provide a machine having a compressor wheel, the rim of which may be removable, when desired.

Another object of the invention is to provide a machine with a compressor wheel which is adapted for adjustment relative to the die assembly.

Another object of the invention is to provide a die assembly consisting of two dies positioned in complementary relation to each other.

Still another object of the invention is to provide a compressor wheel and die assembly which possess structural characteristics for their effective operative alignment at all times.

A still further object of the invention is to provide a machine adapted for producing feeds of uniform density and consistency through more than one die and which is capable of operating at different speeds for the manufacture of different types of feeds without in any way increasing the amount of power consumed.

The invention is directed to other objects, possesses other features of novelty and advantage, and consists in a new and useful formation and construction of elements, all of which will become readily apparent from the following detailed description having reference to the accompanying drawings which illustrate but one embodiment by which the invention may be realized.

In the drawings in which like or corresponding elements are given identical reference characters,

Figure 1 is a front elevation of a machine incorporating the principles of the invention showing the compressing wheel assembly and die assembly in operative contact;

Figure 2 is a front elevation of the machine as shown in Figure 1 with a portion broken away to show the means employed for shifting the compressing wheel assembly toward or away from the die assembly and illustrating the position of the compressing wheel assembly when not in operative contact with the die assembly;

Figure 3 is a sectional, plan view, taken on line 3—3 of Figure 1 looking in the direction indicated, showing the detailed structural characteristics of the compressor wheel and die assemblies;

Figure 4 is a fragmentary, plan view of the machine shown in Figure 1 graphically illustrating the operative contact assumed by the compressor wheel assembly and the die assembly;

Figure 5 is an enlarged fragmentary plan view, diagrammatical in character, of the outer die faces and the compressor wheel faces to permit a more detailed examination of their relationship;

Figure 6 is a side elevation of the machine embodying the invention, with the frame partially broken away, to disclose the means employed in transmitting rotation to the die assembly;

Figure 7 is a perspective view of one of the dies employed in the machine embodying the invention; and

Figure 8 is a perspective view of the compressor wheel assembly employed in the machine embodying the invention, partially in cross-section to show the detailed structural characteristics thereof.

The machine embodied in the drawings consists of a supporting frame designated in its entirety by reference character A. The frame may be secured to a platform or directly to a floor in any manner expedient to the user. The rear wall 1 of frame A is removable, making it possible to examine the interior 2 and, if desired, to remove and replace any part confined therein. The rear wall 1 is securely fastened to the frame A by suitable nut and bolt assemblies 3 which connect the two gasketed flanges 4 and 5. 45 This arrangement insures against leakage of any of the lubricant which is normally confined within the interior 2 for lubricating the bearing and other working elements.

It will be seen from an examination of Figure 2 and particularly of Figure 3 of the drawings that a sleeve 6 is horizontally positioned within the frame A. Sleeve 6 has cam members 7 and 8 made integral with and disposed at the opposite ends thereof. The cams have a common axis 55

and are positioned relative to the sleeve so that their respective peripheries are in coinciding alignment. Cam 7 is positioned in a suitable bearing provided with rear wall 1 and cam 8 is seated within a suitable bearing provided within the front wall 9 of frame A. The sleeve is capable of rotation within the bearing surfaces thus provided in the frame A. To permit the rotation of the sleeve, when desired, a gear wheel 10 section 10 is secured against the supporting stud 11 extending from the sleeve. The teeth of the gear wheel section 10 are at all times in mesh with the worm 12 which is itself substantially confined within the casing 13 formed integrally within frame A. A shaft 14 extends upwardly from the casing 13 and is either made integral with or directly secured to worm 12. This construction contemplates the rotation of the sleeve within its bearings with ease; and, if the sleeve 6 is not frictionally restrained from rotation within the bearing surfaces provided in frame A, it is obvious that the sleeve may easily be rotated by simply rotating the shaft 14. However, since the rotation of the sleeve is mainly desired 25 to provide certain important adjustments and conveniences of assembly and disassembly, provision is made within the frame A to maintain the sleeve against rotation. This is accomplished by splitting the frame A at the bearing provided 30 for cam member 8, as shown at 15, and providing thereat ears 16 and 17 through which a nut and bolt assembly 18 passes. This construction provides a simple but effective manner for anchoring cam member 8 against rotation within its 35 bearing. The functional importance of the sleeve and the desirability of rotating it on its cams will be explained shortly. However, it is well to point out at this time that when the sleeve is in position as shown in Figure 3, the 40 compressor wheel assembly and die assembly are in operative contact with each other and are positioned as shown in Figures 1, 3 and 4. But when the sleeve is positioned as partially shown in Figure 2, the compressor wheel assembly and die assembly are not only out of operative contact with each other, but also are in position for 45 removal from the machine. (The dotted lines shown in this figure graphically indicate the normal operating position of the compressor wheel assembly to the die assembly and the normal position of the sleeve.)

A shaft 19 passes through the sleeve 6 and is positioned for unimpaired rotational movement with respect to its interior 20. A bearing 21 of the ball-bearing type is provided for the rear portion of the shaft 19 and a bearing 22 of the roller bearing type is provided for shaft 19 adjacent its front portion 23, which extends through front wall 9 of frame A. These bearings 21 and 22 are 55 confined within cages 24 and 25 formed in cam members 7 and 8 respectively. A suitable lubricant-retaining plate 26 is secured in any desirable manner to the rear wall 1 and a similar plate 27 is secured to the front wall 9 of frame A surrounding the exposed portion of shaft 19 and effectively retaining suitable packing material therein. These plates not only prevent the loss of any lubricant, but also serve, to a limited extent, to restrain the external movement of the sleeve 6. It 60 will shortly be observed that rotation is imparted to shaft 19 through the contact of the compressor wheel assembly with the die assembly. However, shaft 19 may readily receive its rotational movement directly from a source of power without in 65 any material particular affecting the function 70

and operation of the elements heretofore described.

Another shaft 28, having its front portion 29 extending through wall 9 of frame A, is rotatably positioned within the interior 2 of frame A in 5 parallel, horizontal relationship to shaft 19. A bearing 30 of the ball bearing type is provided for the rear portion of the shaft 28 and a bearing 31 of the roller bearing is provided for shaft 28 adjacent its front portion. These bearings are 10 confined within seats provided in the rear wall 1 and front wall 9 respectively of frame A. A suitable plate 32 is secured to the rear wall 1 by any well-known means and a similar but packing-carrying plate 23 surrounds shaft 28 and is secured in similar fashion to the front wall 9 of frame A. The employment of these plates insures against leakage of the lubricant confined within the interior 2. A pair of gear wheels 34 and 35, possessing different diameters, are secured to shaft 28 and are wholly confined within the interior 2 of frame A.

Still another shaft 36 is journaled within frame A directly above and in parallel alignment with shaft 28. Shaft 36 extends through the rear wall 1 of frame A and is connected directly or indirectly to a source of power (not shown) which gives it the rotation desired. A gear-wheel supporting sleeve 37 is disposed about shaft 36 and is slidably confined within one or more grooves 38 formed in said shaft. Gear wheels 39 and 40 are secured to the sleeve 37 and are identical in all respects except in diameters. The sleeve 37 is movable on the shaft 36 so that the teeth of large gear wheel 39 may mesh with the teeth of small gear wheel 34 positioned on shaft 28 when desired; and, if desired, the sleeve may be shifted so that the teeth of the small gear wheel 40 may mesh with the teeth of the large gear wheel 35 positioned on shaft 28. However, the gear wheels 39 and 40 are so arranged on the sleeve 37 that only one of them at a time can engage with its respective gear wheel found on shaft 28. A gear shift lever 41 is swivelly joined to and passes through the frame A, as shown at 42, and the depending arms 43 (only one of which is shown) are secured to the sleeve 37, as shown at 44. This arrangement controls the gear ratios by which the speed of rotation of the driving shaft 36 is transmitted to the driven shaft 28. The employment of this mode of transmitting power to shaft 28 is believed advantageous because different types of compressed feeds require different operating conditions in order to obtain the greatest efficiency from the machine. It is obvious, of course, that, if desired, shaft 28 may be connected directly to a source of power and entirely eliminate the need of shaft 36 and its related elements.

Attention is now directed to the construction of the compressor wheel assembly designated in its 60 entirety by reference character B. The details of construction can best be observed from an examination of Figures 3 and 8. Compressor wheel B consists of a hub 45 which is keyed or otherwise secured to portion 23 of shaft 19. An annular shoulder 46 extends from one side of the hub 45. The top 47 of shoulder 46 is inclined downwardly toward the other side of the hub and a like inclination, parallel to the inclination of top 47, is formed on the remainder of the hub 45, as shown 65 at 48.

A band or cylindrical rim 49 made of case hardened steel or an alloy treated to resist wear, is removably disposed upon the hub 45. The configuration of the rim, when viewed in cross sec- 70 75

tion, consists of a pair of internal, tapered surfaces 50 and 51 of identical pitch and a pair of external converging surfaces 52 and 53 of equal pitch forming a beveled periphery, the apex of which is occupied by a flat-topped, annular ledge 54. When the rim is in position upon hub 45, inclined surface 50 intimately contacts the top 47 of shoulder 46 and inclined surface 51 is in direct alignment with the remaining inclined surface of the hub. In this manner a slightly wedge-shaped inner recess 55 is formed. An annular ring 56, the sides of which are tapered toward each other to form a partial wedge, snugly fits into the recess 55. Ring 56 is secured to the hub 45 by any desirable means, as by bolts 57. When the ring is thus securely held against the hub 45, the rim 49 is frictionally held against movement on shoulder 46. A retaining plate 58 is securely held against the end of the shaft 19 by any desirable means, as by bolt 59.

The die assembly, designated generally by reference character C, may be best examined by referring to Figures 3 and 7. A hub 60 is keyed or otherwise secured to the end portion 29 of the shaft 28. An annular shoulder 61 extends upwardly from one side of the hub 60. There are two die rings possessing identical structural characteristics. Consequently, a detailed description of one should suffice for the other. However, in order to distinguish one from the other, the reference numerals for one will be primed. Ring dies 62 and 62' are disposed on hub 60 and the inner face of die 62 rests against shoulder 61. These dies may be keyed or otherwise removably secured to the hub. One of the dies is shown in perspective in Figure 7 and for clarity it shall be considered as die 62'. Dies 62 and 62' each have an inclined annular flange 63 and 63' respectively of equal pitch and contain a series of radially disposed passages 64 and 64' respectively extending through the flanges 63 and 63'. These passages may be circular, rectangular, or any other desired cross-sectional shape. An annular cut-out 65 and 65' is formed in sides 66 and 66' of dies 62 and 62' respectively. When dies 62 and 62' are secured to hub 60, the sides 66 and 66' are positioned in complementary intimate contact with each other so that the cut-out portions 65 and 65' coincide and cooperate to form an annular groove 67 between dies 62 and 62'. When the dies 62 and 62' are positioned on the hub 60 as stated, the annular flanges 63 and 63' incline in opposite directions and form a V-shaped area therebetween, when viewed in cross section. These structural characteristics may be fully observed in Figure 5. The dies 62 and 62' are maintained in intimate working relation with each other and are secured to the hub 60 by the ring 68. A plurality of threaded bolts 69 pass through the ring and dies or are threaded into shoulder 61 of hub 60. The die assembly C is retained in fixed working relation with the shaft 28 by retaining plate 70 held against the end of the shaft by any desirable means, as by threaded bolt 71.

A bracket 72 is secured in any desirable manner to the front wall 9 of frame A. Blade-supporting arms 73 and 74 are removably secured to the bracket by any suitable means and have fingers 75 and 76 respectively inclined and extended inwardly toward each other. These fingers are positioned with respect to the arms so that they are positioned in spaced but parallel relation to inclined inner faces 77 and 77' of dies 62 and 62' respectively. Blades 78 and 79 are removably secured to fingers 75 and 76 respectively and are

adapted to angularly contact the inclined inner faces of 77 and 77' as best shown in Figures 1 and 2. These fixed knives are adapted, not only to sever the compressed material as it is extruded through the passages of the die, but also to direct 5 the cut feeds away from the dies.

The material to be processed into feeds is fed into the space provided between the compressor wheel B and die assembly C when the two are positioned as shown in Figures 1, 3 and 4, the 10 space being fully disclosed in Figure 4. In order to direct the material to be processed toward the space referred to, any desirable structure may be employed and, for example, there is shown in the drawings a chute 80 having the contours desirable for fulfilling the function of feeding small proportions of materials into the space formed between the compressor wheel and die assembly. 15

When the compressor wheel assembly B and die assembly C are in the positions shown in 20 Figures 1, 3 and 4, the peripheral ledge 54, the width of which is slightly smaller than the width of the groove 67 formed between dies 62 and 62', rides within the said groove. To insure an unimpaired trackway for the ledge in said groove, a 25 bar 81 has its wedge-shaped end 82 positioned within the groove 67, and its other end 83 is forked so that it may ride on the ledge 54. As the compressor wheel and die assembly rotate, the bar removes the material which may cling to the 30 ledge and remain in the groove when feeds are being manufactured.

This completes the detailed description of the invention. The operation of the machine is as follows:

When the machine is in the position shown in 35 Figures 1, 3 and 4, the ledge 54 rides within the groove 67; and the faces 52 and 53 of rim 49 contact faces 63 and 63' of dies 62 and 62' respectively, so that when shaft 28 is rotated, rotation 40 is imparted to shaft 19 through the frictional engagement of the compressor wheel B with the die assembly C, as stated. The compressor wheel B and die assembly C, are rotated in converging or opposite directions as shown by the arrows in 45 Figures 1 and 2. Since the compressor wheel B and the dies are circular, they contact each other in tangential relationship. The space provided immediately above the point of contact is employed for delivery of the material to be processed upon the die faces. The material to be 50 processed is delivered through the medium of the chute 80 into said space and said material is immediately trapped between the peripheral surfaces of the dies and the compressor wheel, by 55 the ample tractive force resulting from the rotation of the two bodies in converging relationship. As the compressor wheel B and the die assembly C rotate, a squeegee, wedge-like action is applied to the mass delivered into the space and 60 the material is forced under a uniform degree of pressure through the passages in the dies. The cooperating relationship of the compressor wheel B and the die assembly C results in an equal distribution of pressure during the compressing operation so that no rearward or forward thrust is created during the operation of the machine. 65 The frictional engagement and wedging action between the external, peripheral faces of the compressor wheel B and the die assembly C may be 70 graphically examined in Figure 5.

The groove 67 is of sufficient depth to permit the annular ledge or rib 54 to extend freely therein when the cams 7 and 8 are moved by the actuation of the shaft 14 to adjust the compres- 75

sor wheel assembly B relative to the die assembly C. Further, the depth of each of the teeth on the gear 10 is such that the same will mesh with the pinion on the shaft 14 when the clamping members 16 and 17 are loosened by the bolt 18 to permit the cams 7 and 8 to be rotated to control or adjust the operative contact of the confronting surfaces of the compressor member B and the die member C.

10 It will be seen that the through openings or 15 passages 64 in the inclined flanges 63 and 63' extend substantially at right angles to the inner sides of these flanges, and are disposed to conduct the moldable material in the form of pellets, from 20 the space or chamber above the contacting surfaces of the revoluble members B and C, to opposite sides of the member B. Thus, the bottom of the groove 67 is closed so that the pellets may 25 be extruded laterally from one or both sides of the compressor member B during the operation of the machine.

Compensation for wear of the peripheral surfaces on the dies and the ring 49 may be made by moving the whole sleeve assembly 6 until the 25 desired relationship is obtained between the compressor wheel B and the die assembly C. The most efficient pressure essential for production of different types of feeds can be obtained between the dies and the compressor wheels by the 30 same manipulation of the sleeve assembly 6, and the compressor wheel B may be completely removed from operative relationship and into the position shown in Figure 2 in order to remove either the compressor wheel B or the die assembly C or both from the machine for replacement or other purposes.

From the foregoing description it will appear that the invention as described satisfies the objects set forth herein. The invention has been 40 described in connection with a specific embodiment disclosing a definite arrangement of parts. However, it should be understood that many variants thereof are possible to those skilled in the art. The invention, therefore, in its broader aspect, is not limited to the specific construction 45 herein shown and described, as changes and alterations may be made in the proportions, configurations, and arrangements of the various parts without departing from the broad spirit of this 50 invention.

Having thus described my invention, what I claim as new and upon which I desire to secure Letters Patent is:

1. In a machine of the class described, a pair 55 of spaced revoluble members having outer peripherally disposed, inclined and interfitting contacting surfaces, the space adjacent the contacting surfaces constituting a material receiving chamber, means for feeding moldable material into said chamber, one of said members having a plurality of openings in the inclined sides thereof, said openings during operation of the machine communicating with said chamber, and means for rotating said members in opposite directions so that the material delivered to said chamber is compressed and extruded through said openings to the side of the machine.

2. In a machine of the class described, a pair 70 of spaced horizontally aligned revoluble members having outer peripherally disposed, inclined and interfitting contacting surfaces, the space above the contacting surfaces constituting a material receiving chamber, means for feeding moldable material into said chamber, one of said members 75 having a plurality of openings in the inclined

sides thereof, said openings during operation of the machine communicating with said chamber, and means for rotating said members in opposite directions so that the material delivered to said chamber is compressed and extruded through 5 said openings to the sides of the machine.

3. In a molding machine of the class described, a pair of spaced revoluble members having outer peripherally disposed, inclined and interfitting contacting surfaces, the space adjacent the contacting surfaces constituting a material receiving chamber, means for feeding moldable material into said chamber, one of said members having a plurality of openings in the inclined sides thereof, said openings during operation of the machine communicating with said chamber, means for rotating said members in opposite directions 10 so that the material delivered to said chamber is compressed and extruded through said openings in the form of pellets to the sides of the 15 machine, and means for severing the pellets as they issue from said openings.

4. In a molding machine of the class described, a pair of spaced revoluble members having outer peripheral interfitting and inclined contacting 25 surfaces, the space adjacent the contacting surfaces constituting a material receiving chamber, means for feeding moldable material into said chamber, one of said members having a plurality of openings in the inclined sides thereof, said openings arranged during the operation of the machine to communicate with said chamber, means for rotating said members in opposite directions 30 so that the material delivered to said chamber is compressed and extruded through 35 said openings in the form of pellets to the sides of the machine, and means for adjusting one of the members relative to the other to control the operative contact of said members.

5. In a molding machine of the class described, 40 a pair of spaced horizontally aligned revoluble members having outer peripherally disposed, inclined and interfitting contacting surfaces, the space adjacent the contacting surfaces constituting a material receiving chamber, means for feeding moldable material into said chamber, one of 45 said members having a plurality of openings in the inclined sides thereof, said openings during the operation of the machine communicating with said chamber, means for rotating said members 50 in opposite directions so that the material delivered to said chamber is compressed and extruded through said openings in the form of pellets to the sides of the machine, means for severing the pellets as they issue from said openings, 55 and means for adjusting one of the members relative to the other to control the operative contact of said members.

6. In a pellet forming machine of the class 60 described, a revoluble compression member, a coacting revoluble die member, said die member having spaced peripheral flanges provided with converging opposed inner surfaces terminating in an annular groove, each of said flanges having openings extending therethrough, said compression member having complementary tapered peripheral surfaces engaging the converging surfaces of said die member, the space above the 65 contacting surfaces of said members constituting a chamber for receiving moldable material, means for feeding the material to said chamber, and means for rotating said members in opposite directions so that the material delivered to 70 said chamber is compressed and extruded 75

through said openings in the form of pellets from opposite sides of the machine.

7. In a pellet forming machine of the class described, a revoluble compression member, a coacting revoluble die member, said die member having spaced peripheral flanges, at least one of said flanges having openings extending therethrough, said die member arranged to engage peripherally the compression member between said flanges, the space above the contacting surfaces of said members constituting a chamber for receiving moldable material, means for feeding the material into said chamber, and means for rotating said members in opposite directions so that the material delivered to said chamber is compressed and extruded through said openings in the form of pellets.

8. In a pellet forming machine of the class described, a revoluble compression member, a coacting revoluble die member, said die member having spaced peripheral flanges, said flanges having openings extending therethrough, said die member arranged to engage peripherally the compression member between said flanges, the space above the contacting surfaces of said members constituting a chamber for receiving moldable material, means for feeding the material into said chamber, and means for rotating said members in opposite directions so that the material delivered to said chamber is compressed and extruded through said openings in the form of pellets.

9. In a pellet forming machine of the class described, a revoluble compression member, a coacting revoluble die member, said die member having spaced peripheral flanges provided with converging opposed inner surfaces terminating in an annular groove, each of said flanges having openings extending therethrough, said compression member having complementary tapered peripheral surfaces engaging the converging surfaces of said die member, said tapered surfaces terminating in a medially disposed projection extending into said annular groove, the space above the contacting surfaces of said member constituting a chamber for receiving moldable material, means for rotating said members in opposite directions so that the material delivered to said chamber is compressed and extruded through said openings in the form of pellets from opposite sides of the machine, cammed means for adjusting the compression member relative to the die member to control the operative contact of said surfaces, and means for actuating said cammed means.

10. In a pellet forming machine of the class described, a revoluble compression member, a coacting revoluble die member, said die member having spaced peripheral flanges provided with converging opposed inner surfaces terminating in an annular groove, each of said flanges having openings extending therethrough substantially at right angles to the converging inner surfaces, said compression member having complementary tapered peripheral surfaces engaging the converging surfaces of said die member, said tapered surfaces terminating in a medially disposed projection extending into said annular groove, the space above the contacting surfaces of said member constituting a chamber for receiving moldable material, means for rotating said members in opposite directions so that the material delivered to said chamber is compressed and extruded through said openings in the form of pellets from opposite sides of the machine,

means for adjusting the compression member relative to the die member to control the operative contact of said surfaces, and means for severing the pellets as they issue from said openings.

11. In a pellet forming machine of the class described, a revoluble compression member, a coacting revoluble die member, said die member having spaced peripheral flanges provided with converging opposed inner surfaces terminating in an annular groove, each of said flanges having openings extending therethrough, said compression member having complementary tapered peripheral surfaces engaging the converging surfaces of said die member, said tapered surfaces terminating in a medially disposed projection extending into said annular groove, the space above the contacting surfaces of said member constituting a chamber for receiving moldable material, means for rotating said members in opposite directions so that the material delivered to said chamber is compressed and extruded through said openings in the form of pellets from opposite sides of the machine, means for adjusting the compression member relative to the die member to control the operative contact of said surfaces, and means for preventing material adhering to the surfaces of said groove and projection during the operation of the machine.

12. In a pellet forming machine of the class described, a revoluble compression member, a coacting revoluble die member, said die member having spaced peripheral flanges forming a continuous groove therebetween, each of said flanges having transverse openings extending therethrough, said compression member having its peripheral surface extending into and contacting with said groove to form a moldable material receiving chamber above the points of contact of said members, means for feeding the moldable material to said chamber, and means for rotating said members in opposite directions so that the material delivered to said chamber is compressed and extruded through said openings in the form of pellets from opposite sides of the machine.

13. In a pellet forming machine of the class described, a revoluble compression member, a coacting revoluble die member, said die member having spaced annular flanges provided with converging inner sides terminating in an annular groove, each of said flanges having openings extending therethrough, said compression member having a rim provided with complementary formed converging sides engaging the converging sides of said die member, said rim having an annular projection extending into said groove, the space above the contacting surfaces of said members constituting a chamber for receiving moldable material, means for feeding the moldable material into said chamber, means for rotating said members in opposite directions so that the material delivered to said chamber is compressed and extruded through said openings in the form of pellets from the opposite sides of the machine, and means for preventing the material adhering to the surfaces of said grooves and said rib.

14. In a molding machine of the class described, a revoluble compression member, a coacting revoluble die member, said die member including a hub, a pair of discs secured to the hub, said discs having spaced annular flanges provided with converging surfaces terminating in an annular groove, each of said flanges having openings ex-

tending transversely therethrough, said compression member having complementary inclined surfaces engaging the converging surfaces of said die member, said rim being provided with a medially disposed projection extending into said groove, means for removably connecting the rim to the compression member, the space above the contacting surfaces of said members constituting a chamber for receiving moldable material, means for feeding the material to said chamber, means for rotating said members so that the material delivered to said chamber is extruded through said openings in the form of pellets from opposite sides of the machine, and cammed means operatively connected to the compression member for adjusting the same relative to the die member.

15. In a molding machine of the class described, a revoluble compression member, a co-acting revoluble die member, said die member including a hub, a pair of discs secured to the hub, said discs having spaced annular flanges provided with converging surfaces terminating in an annular groove, each of said flanges having openings extending transversely therethrough, said compression member having complementary inclined surfaces engaging the converging surfaces of said die member, said rim being also provided with a medially disposed projection extending into said groove, removable means for connecting the rim to the compression member, the space above the contacting surfaces of said members constituting a chamber for receiving moldable material, means for feeding the material into said chamber, means for rotating said members so that the material delivered to said chamber is extruded through said openings in the form of pellets from opposite sides of the machine, means operatively connected to the compression member for adjusting the same relative to the die member, and means for severing the pellets as they issue from said openings.

16. In a molding machine of the class described, a revoluble compression member, a co-

acting revoluble die member, said die member including a hub, a pair of discs secured to the hub, said discs having spaced annular flanges provided with converging surfaces terminating in an annular groove, each of said flanges having openings extending transversely therethrough, said compression member having complementary inclined surfaces engaging the converging surfaces of said die member, said rim being also provided with a medially disposed projection extending into said groove, means for detachably connecting the rim to the compression member, the space above the contacting surfaces of said members constituting a chamber for receiving moldable material, means for feeding the material to said chamber, means for rotating said members so that the material delivered to said chamber is extruded through said openings in the form of pellets from opposite sides of the machine, means operatively connecting with the compression member for adjusting the same relative to the die member, means for severing the pellets as they issue from said openings, and means for preventing material adhering to the surfaces of said groove and rib during the operation of the machine.

17. A revoluble compression member to be used with a molding machine of the class described, comprising, a hub having an annular, downwardly inclined shoulder, a cylindrical rim removably disposed on said hub, said rim having complementary inclined converging outer peripheral surfaces, a medially disposed projecting annular ledge extending upwardly at the convergence of said inclined surfaces, and removable means for connecting the cylindrical rim to the hub.

18. A revoluble die member to be used with a molding machine of the class described, comprising, a hub, and a pair of discs having spaced annular flanges provided with converging surfaces terminating in an annular groove, each of said flanges having openings extending transversely therethrough.

DUANE CRABTREE
